MAGAZINE SAFETY RAZOR

John F. Cavanagh, Cranston, R. I.

Application June 5, 1951, Serial No. 230,011

12 Claims. (Cl. 30—40)

1

This invention relates to improvements in safety razors and has for its objects:

First, to provide a magazine razor holding a plurality of razor blades, with incorporated means for instantly replacing a used blade.

Second, a magazine razor incorporating means for storing used razor blades.

Third, a magazine razor wherein manual contact with blades is obviated.

Fourth, a safety razor of economical construction embodying the foregoing features.

With these objects in view, certain other novel features and advantages will be explained as the specification proceeds.

In the accompanying drawings:

Fig. 1 is an outside front elevation of the razor.

Fig. 2 is an outside side elevation of the razor.

Fig. 3 is an enlarged end view, showing a blade in shaving position.

Fig. 4 is a cross sectional view through the lower conveyor drum, on line 4—4 of Fig. 6.

Fig. 5 is an enlarged elevation, with the casing in section, showing the chassis retracted.

Fig. 6 is a view similar to Fig. 5, but with the chassis in normal position.

Fig. 7 is a cross sectional view, taken on line 7—7, of Fig. 5.

Fig. 8 is a plan view of an enlarged portion of the blade conveyor.

Fig. 9 is an enlarged sectional detail taken on line 9—9, of Fig. 8.

At present there is an insistent demand for a safety razor wherein a used blade may be readily replaced by a fresh one.

To meet this demand several widely used brands provide a blade package with incorporated means for sliding a blade from the package into shaving position in the razor. In many instances there is no provision for preventing the discarded blade from becoming a hazard, especially to children.

In my improved razor, the advantages of unitary construction preclude manual handling of individual blades, several months supply of blades being enclosed in a locked casing.

The construction is such that the razor may be produced so economically as to be expendable, as a unit, when the supply of blades has been used in shaving.

Attention is called to the important advantage of provision for re-use of the entire supply of blades should the user find himself temporarily removed from a source of supply for new razors.

This latter advantage together with the fore-

2

going features make this razor highly suitable for use by our armed forces.

Referring to the drawings, 10 is the body portion of a casing. 11 is a telescoping cover, adapted to fit tightly over and be inseparably attached to said body portion by indentations, or other commonly utilized means, not shown.

Within the casing 10, 11, is a chassis 12, consisting of a pair of similar spaced sides 13 and 14, shown in section in Fig. 4 and Fig. 7.

Rotatably mounted on pins 15, at each end of said chassis 12, are upper conveyor drum 16 and lower conveyor drum 17, for a purpose about to be explained.

15 The overlapping sides of casing body 10 and casing cover 11, are so shaped as to provide slots 18, best shown in Fig. 2, for the purpose of receiving the ends of pins 15, thereby providing for a predetermined amount of guided chassis displacement.

Referring to Fig. 4 and Fig. 8, 19 is one of a plurality of single edge razor blades, provided at each end with a clip 20, adapted to be compressed around the end of blade 19, after flexible cable 21 has been passed between the lips of said clip 20, as shown. The compressing operation securely locks blades 19 to cable 21.

By utilizing two strands of cable in the foregoing manner an endless band 22 of flexibly connected, accurately spaced razor blades may be produced, as shown in Fig. 5 and Fig. 6.

Such a band is adaptable to production on automatic machines.

Referring to Fig. 5, Fig. 6, and Fig. 7, it will be seen that conveyor drums 16 and 17 are provided with facets 23, contacting the blades of band 22, and nests 24, for clips 20.

The distance between conveyor drums 17 and 18 is adapted to provide the correct degree of 40 band tension when endless band 22 is mounted on said drums 17 and 18.

In mounting band 22 on chassis 12, the correct length of band assembly with free cable at each end is first provided.

45 Referring to Fig. 8, 25 is a cable connector, provided at each end with bifurcated portions, forming cable retainers, adapted to be compressed around the ends of cables 21, as shown in Fig. 9.

50 The band assembly is mounted upon drums 17 and 18, and the free cable ends are positioned in the cable retainers of cable connector 25, as shown in Fig. 8, and the foregoing cable retainer portions of cable connector 25 are compressed around cable 21.

The protruding cable ends are then clipped flush with the ends of cable connector 25, when the chassis sub-assembly is complete and ready to be inclosed by casing members 10 and 11.

Referring to Fig. 5 and Fig. 6, 26 and 27 are the two links of a toggle, tied together by pivot 28, as shown.

The toggle link 26 is pivoted on casing body 10 by pin 29, while toggle link 27 is pivoted to chassis 12 by pin 30, as shown in Fig. 7.

A slot 37, in casing body 10, accommodates toggle links 26 and 27 in their released position.

Projection 31, on toggle link 26, is provided with a formed end 32, which acts as a stop for the swing of said toggle link 26, in its locked position and also provides means for operating by thumb nail engagement.

It will be seen that the said toggle links 26 and 27 function to cause chassis 12, to slide within casing 10, 11, the predetermined distance represented by the length of slots 18, and that a powerful thrust is exerted upon chassis 12, as pins 28, 29, and 30, become aligned.

It will also be seen that the characteristic self-locking action of toggle linkage is taken advantage of to hold chassis 12 normally in the position indicated in Fig. 6.

Referring to Fig. 3 and Fig. 5, it will be seen that casing body 10 is provided with resilient lip 33, which serves to clamp a razor blade against its corresponding facet on upper conveyor drum 16, when chassis 12 is forced upward through the action of toggle links 26 and 27.

Casing cover 11 is also provided with a resilient lip 34, which serves to clamp the razor blade adjacent to the above mentioned clamped razor blade against its corresponding facet on conveyor drum 16.

The angular relationship of adjacent facets on conveyor drum 16, are such that the back edge of any blade in band 22, will function as a guard for the adjacent cutting edge of a neighboring blade in the operation of shaving.

Fig. 5 shows a resilient pawl 35, riveted to casing body 10, with its free end adapted to engage the clips 20, of band 22, and serve to index said band 22, when chassis retracts through the manipulation of toggle links 26 and 27.

Assuming that all parts are in normal position as shown in Fig. 6, and that a fresh razor blade is required, it is simply necessary to move toggle link 26, into position indicated in Fig. 5, and then return said link 26, to the normal position shown in Fig. 6.

This operation first retracts chassis 12 a distance sufficient to permit conveyor drum 16 to turn with band 22, free from contact with resilient lips 33 and 34.

As chassis 12 is farther retracted, resilient pawl 35 engages a clip 20, in band 22, causing said band 22 to be displaced the exact amount to insure a fresh blade being positioned under lip 33, and an adjacent blade being similarly positioned under lip 34. Returning link 26 to normal position causes chassis 12 to be forced in the direction of said lips 33 and 34, thereby firmly clamping a fresh blade in position for shaving.

The relationship of lips 33 and 34, on casing 10, 11, is such as to provide an opening 36, in which the razor blades in band 22 are successively exposed as shown. In assembling the parts of the razor, the blade adjacent cable connector 25 is positioned for the first shaving operation. As succeeding razor blades in band 22 are utilized,

cable connector 25 will eventually re-appear, thus indicating the usage of all the blades in band 22.

I claim:

5. A razor comprising a casing, a conveyor drum rotatably mounted in each end of said casing, an endless band consisting of flexibly connected single edge razor blades mounted upon said drums, an opening in said casing adjacent 10 to the periphery of a drum, said opening adapted to expose a blade edge for shaving action, the spacing of said razor blades in said band being such that the back edge of any blade constitutes a guard for the cutting edge of a juxtaposed 15 blade when said juxtaposed blade is in shaving position, and means for successively placing said blades in shaving position with respect to said opening in said casing.

2. In an implement for shaving, a casing provided with an opening near its end, a chassis 20 slidably mounted within said casing, an endless band consisting of a plurality of flexibly connected razor blades, means for displaceably mounting said band on said chassis, and means 25 responsive to sliding the chassis with reference to said casing for moving said band on said chassis to successively position said blades at said opening in said case for the operation of shaving.

3. In an implement for shaving, a chassis 30 provided with conveyor drums, an endless band comprising flexibly connected single edge razor blades, means for displaceably mounting said band upon said conveyor drums, a casing surrounding said chassis, an opening in said casing 35 adjacent to a conveyor drum, the spacing of said blades in the band being such that the flexing of said band over the periphery of said drum will present a shaving relationship between the cutting edge of any blade and the back edge of its juxtaposed blade with the latter constituting a guard for the cutting edge of the juxtaposed blade.

4. In an implement for shaving, a casing provided with an opening at one end, a chassis 45 slidably retained in said casing, a conveyor drum mounted at each end of said chassis, an endless flexible band incorporating a plurality of blades, means for displaceably retaining said band on said drums, a clamping element juxtaposed to said opening in said casing, and means for longitudinally moving said chassis to cause a blade 50 in said band to be bound between said clamping element and its corresponding drum.

5. In an implement for shaving, a casing provided with an opening at one end, a chassis longitudinally slidable in said casing, a conveyor drum mounted at each end of said chassis, an endless band incorporating a plurality of blades, means for displaceably retaining said band on said drums, a blade clamping element juxtaposed to said opening in said casing, and means whereby the longitudinal movement of said chassis will automatically release said blade clamping element, index said endless band and restore said blade clamping element.

6. In an implement for shaving, a casing provided with an opening at one end, a chassis longitudinally slidable in said casing, a conveyor drum mounted at each end of said chassis, an endless band displaceably mounted on said drums incorporating a plurality of flexibly connected razor blades, a blade clamping element juxtaposed to said opening in said casing, means for forcing said chassis toward said clamping element for the purpose of clamping a blade between said

clamping element and its corresponding drum, means for indexing said flexible band a predetermined distance, and means whereby the manipulation of a single element will successively cause said chassis to move away from said blade clamping element, index said flexible band, and restore said chassis to clamping relationship with said clamping element.

7. In an implement for shaving, a casing provided with an opening, a chassis slidably retained in said casing, a conveyor drum mounted at each end of said chassis, an endless flexible band incorporating a plurality of blades, means for displaceably mounting said flexible band on said drums, a clamping element juxtaposed to said opening in said casing, a toggle for normally retaining said chassis in predetermined relationship to said clamping element, and means whereby the manipulation of said toggle will cause said chassis to move away from said clamping element for the purpose of indexing said flexible band, and restore said chassis to normal relationship to said clamping element.

8. In an implement for shaving, a casing provided with an opening at one end, a chassis longitudinally slidable in said casing, a conveyor drum mounted at each end of said chassis, an endless band incorporating a plurality of blades, means for displaceably retaining said band on said drums, a blade clamping element juxtaposed to said opening in said casing, an element attached to said casing whereby the longitudinal movement of said chassis will cause the said flexible band to be indexed a predetermined distance with respect to its position on said chassis.

9. In an implement for shaving, a casing provided with an opening at one end, a chassis longitudinally slidable in said casing, a conveyor drum mounted at each end of said chassis, an endless band incorporating a plurality of blades, means for displaceably retaining said band on said drums, a blade clamping element juxtaposed to said opening in said casing, a manually operated member adapted to cause the succession of events

represented by release of said blade clamping element, indexing of said endless band and restoration of said blade clamping element.

10. A razor comprising a casing having an opening therein, a chassis slidably mounted in said case, a plurality of flexibly attached blades guided by said chassis, means to advance said blades with reference to said chassis upon reciprocatory sliding movement of the chassis to present a succeeding blade of the plurality to the opening in said case.

11. A razor comprising a casing having an opening therein, a chassis slidably mounted in said case, a plurality of flexibly attached blades guided by said chassis, means to advance said blades with reference to said chassis upon reciprocatory sliding movement of the chassis to present a succeeding blade of the plurality to the opening in said case and means to bind a blade between the chassis and case as the chassis is slid into the casing with the bound blade projecting through said opening.

12. A razor comprising a casing, a chassis mounted in said casing, an endless band consisting of flexibly connected single edge razor blades mounted upon said chassis, an opening in said casing adjacent to one end of said chassis, said opening adapted to expose a blade edge for shaving action, the spacing of said razor blades in said band being such that the back edge of any blade constitutes a guard for the cutting edge of a juxtaposed blade when said juxtaposed blade is in shaving position, and means for successively placing said blades in shaving position with respect to said opening in said casing.
